RADIO FREQUENCY COIL

Application filed November 25, 1925. Serial No. 71,379.

The invention relates to radio-frequency coils and more particularly to shielding and coupling means for such coils.

An object of the invention is to provide 5 a novel form of shielding means to screen a radio receiving inductor from the influence of powerful radio frequency fields, thereby improving selectivity in a receiving circuit embodying such inductor.

10 Another object of the invention is to utilize such shielding means as a coupling means to an input or collector circuit.

A further object of the invention is to 15 utilize such shielding means as a control for oscillation in a receiving circuit.

The invention further consists in the several features hereinafter set forth and more particularly defined by the annexed claims.

In the accompanying drawings, Fig. 1 is 20 a diagrammatic view of a radio receiving circuit including the shielded coil of the present invention;

Fig. 2 is a longitudinal sectional view 25 through a coil embodying the invention; and Fig. 3 is a transverse sectional view thereof taken on the line 3—3 of Fig. 2.

In these drawings, 10 indicates a hollow supporting form of suitable insulating material, such as hard rubber, upon which is 30 wound a coil 11 preferably disposed in spaced coil sections 12 and 13. If desired, the supporting form 10 may be of skeletal character in order to minimize di-electric losses, or in some instances the coil may be of 35 self-supporting character. In the present case, the ends of the coil are connected to terminal posts 14 and 15, respectively, which are preferably disposed at opposite ends of the supporting form 10.

40 The coil sections 12 and 13 are surrounded by annular metal shields 16 and 17, respectively, each carrying a terminal post 18. The shields are preferably slightly spaced from the winding and are each provided with a 45 gap 19 in order to minimize eddy currents.

With these provisions, the high frequency resistance of the coil is not unduly increased. In the present instance, each shielding band is provided with inturned flanges 20 at opposite edges to bear on the supporting form

10, but in some cases the shield may be supported upon the winding, if interposed insulation is provided. The coil sections are preferably disposed in adjacent inductive relation as shown, but it is not essential that 55 they occupy this relation.

In the diagram of Fig. 1, the coil forms part of an "ultra-audion" receiving circuit including a three-element thermionic detector tube 21, the coil being tuned by a variable condenser 22. As is well known, this circuit provides "automatic" regeneration but is somewhat unstable because of a marked tendency towards oscillation. It is found, however, that the shielding means of the 60 invention serves to stabilize the circuit by reason of the presence of such means in the radio-frequency field of the coil. The coil may, of course, be used in various other 65 types of circuits.

The shield 16 is connected by its binding post 18 to an antenna 23 while the shield 17 is connected to a ground 24. The collector circuit thus comprised may also include tuning elements, such as a variable inductor 25. 70 However, the inductor 25 may be omitted in some instances. With the above-described connections the shields form coupling elements by which the coil is electrostatically coupled to an input circuit, such 75 as the collector circuit shown in the diagram. Under adverse conditions the shield 16 may surround a relatively small part of the total coil winding, and in some instances the entire coil may be surrounded by a single 80 shield.

The present invention accordingly provides a shielding means for improving selectivity by minimizing or eliminating local 90 "pick-up" incident to the collector characteristic of an exposed coil, and affords means for coupling the coil into another circuit and for controlling the tendency towards oscillation in certain types of receiving circuits.

95 What I claim as new and desire to secure by Letters Patent is:

1. The combination with a solenoidal radio-frequency coil and a tubular supporting form therefor, of a discontinuous an- 100

5 nular metallic shielding band surrounding said coil and having inturned flanges at opposite edges beyond the ends of the coil resting on said tubular supporting form.

10 5. The combination of a radio-frequency coil having spaced solenoidal coil sections, and annular metallic shielding members each surrounding a coil section and being wider than said coil section and both annular members forming coupling elements for said coil sections.

15 6. The combination of a solenoidal radio-frequency coil forming part of a receiver input circuit, and a pair of discontinuous annular metallic shielding bands surrounding different sections of said coil and each being wider than its co-operative coil section, one of said annular bands forming an antenna coupling element for transferring 20 signal energy to said input circuit and the other band forming a ground coupling element.

25 7. The combination of a solenoidal radio-frequency coil forming a part of a receiver input circuit, and an annular metallic band surrounding said coil out of electrical contact therewith and having its adjacent ends out of contact, said metallic band lying adjacent the coil to form an electrostatic coupling element for transferring radio-frequency signal energy to said coil and being wider than the coil to form a shielding element.

30 8. The combination with a tunable regenerative radio-frequency receiving circuit, of an inductor in said circuit, and a metallic shielding band surrounding said inductor and forming a means for preventing oscillation in said circuit and for transferring signal energy to said inductor.

35 In testimony whereof, I affix my signature.

ALFRED E. BAUMANN.
